UNITED STATES PATENT OFFICE.

FRED E. WEED, OF COLUMBIA, MISSOURI.

PAPER ELEVATOR FOR PRINTING AND FOLDING MACHINES.

Application filed April 20, 1921. Serial No. 462,983.

To all whom it may concern:

Be it known that I, FRED E. WEED, a citizen of the United States, residing at Columbia, county of Boone, and State of Missouri, have invented certain new and useful Improvements in Paper Elevators for Printing and Folding Machines, of which the following is a specification.

This invention relates to improvements in a paper elevator for printing and folding machines.

The main object of the invention is to provide a paper elevator that is automatic in operation depending upon the speed at which the paper is fed to the printing or folding machine and wherein means are provided to render the elevator inoperative when the feeding operation is discontinued notwithstanding the fact that the printing or folding machine may continue in operation.

Another object of the invention is to provide a vertically movable platform to receive the paper that is fed to the printing or folding machine and means to normally rest on the top of the bulk of paper to control the movement of the platform thus insuring elevation of the platform only after a predetermined quantity of the papers has been fed to the printing or folding machine.

A further object of the invention is to provide an elevator of the character described that is applicable to conventional types of printing and folding machines and which may also be used to advantage in connection with the feeding mechanism for printing and folding machines covered in my co-pending application filed October 8th, 1920, Serial Number 417,668.

A still further object of my invention is to provide an automatic elevator of the above character that is simple in construction, strong and durable and which may be produced at a low cost.

Various other objects and advantages of my invention will become apparent during the continuance of the following description.

In the drawings:—

Figure 1 is a view in side elevation showing my invention in its preferred embodiment.

Figure 2 is a view in top plan.

Figure 3 is a view in vertical longitudinal cross section taken on line 3—3 of Figure 2.

Figure 4 is a view in transverse cross section taken on line 4—4 of Figure 2.

In the drawings, 10 designates the stand or body portion of the elevator which may be constructed of any suitable or desirable material and designed in any novel or peculiar manner. On opposite sides, the body portion or stand 10 carries suitably formed guide and supporting members 11 and 12 respectively which have supporting heads 13 located at the bottom thereof as clearly shown in Figures 3 and 4. The guide members 11 and 12 are further provided with vertically extending channels 14 and 15, the purpose of which will presently appear.

On opposite sides of the top, the base or stand 10 carries upstanding bearing members 16 and 17 which support a transverse operating shaft 18. Longitudinal movement of the shaft 18 with respect to the bearing members 16 and 17 is prevented by means of collars 19, 20, 21 and 22 which are fixed to the shaft and positioned on each side of the bearing portions as shown to advantage in Figure 2. The shaft 18 also carries oppositely arranged bevelled gears 23 and 24 which are fixed thereto and arranged in spaced relation to each of the bearing portions 16 and 17 and serve the purpose that will presently appear.

Worm shafts 25 and 26 have their lower ends journaled in the heads 13 of the members 11 and 12 while their upper end is journaled in supplemental bearing portions 27 and 28 which are carried on the bearing portions 16 and 17 and secured in place by means of fastening members 29 and 30. At their upper end the worm shafts 25 and 26 are provided with bevelled gears 31 and 32 which mesh with the bevelled gears 23 and 24 that are carried on the shaft 18. Consequently when the shaft 18 is rotated, a similar movement will be transmitted to the worm shafts 25 and 26.

A platform 33 is also provided and carries extensions 34 and 35 which project into the channels 14 and 15 respectively of the members 11 and 12 and which have screw threaded openings to receive the worm shafts 25 and 26 as clearly shown in Figure 4. A platform which receives the paper to be fed to the printing or folding machines in connection with which the elevator is used and which in the present embodiment I have designated by the numeral 36 so that when the shafts 35 and 36 are rotated in the proper direction, the platform 33 will be moved upwardly so as to feed the paper which is ear-

ried thereon to the other mechanism of the machine, as is obvious.

On one of its projecting ends and in spaced relation to the collar 22, the shaft 18 carries a ratchet wheel 36 which is keyed thereto so as to operate with the shaft. Adjacent the ratchet wheel the shaft also carries a loosely mounted disc wheel 37 which has a cam extension 38 mounted adjacent the periphery thereof for the purpose that will presently appear.

In order to rotate the shaft 18, I provide the same with a depending arm 39 which is loose on the shaft so that it may be rocked and which carries a pawl 40 that normally engages the ratchet wheel 36 as clearly shown in Figure 1. Consequently by rocking the arm 39, the pawl 40 will, acting on the teeth of the ratchet wheel, cause the wheel to be rotated and impart a light movement to the shaft 18. An actuating arm 41 is adjustably connected to the arm 39 as at 42 in order to operate the arm 39. The connection between the arm 41 and the arm 39 is adjustable so that the throw of the arm 39 may be regulated and thereby adjust the throw of the pawl 40 with respect to the ratchet wheel 36. The arm 41 is attached to suitable mechanism on the printing or folding machine which will cause the arm 41 to reciprocate continually during the operation of the machine.

It will be observed upon reference to Figure 4 that the cam extension 38 of the disc wheel 37 is in line with the pawl 40 of the arm 39 so that when the disc wheel 37 is given a partial rotation, the cam can be brought into engagement with the pawl 40 so as to force the same out of engagement with the ratchet wheel 36. When the disc wheel is in such position and the pawl 40 is out of engagement with the ratchet wheel 36, it will be noted that the movement of the arm 39 will not cause a rotation of the ratchet wheel 36 and the shaft 38. However when the disc wheel 37 has been moved to its normal position and the pawl 40 has been released, the rotation of the shaft 18 will continue.

I also provide means to operate the disc wheel 37 so as to control the engagement of the pawl 40 with the ratchet wheel 36 as the feeding operation of the paper on the platform 33 continues. With this in view, I provide the stand or body portion 10 with a transverse shaft 43 which is located on the top thereof and near the front as shown in Figure 2. The shaft is carried in bearings 44 and 45 and one end projects beyond the base or stand 10 preferably on the side opposite the ratchet wheel 36 and the disc wheel 37. Intermediate its ends and between the bearing portions 34 and 35, the shaft 33 carries a depending arm 46 which is in turn provided at its lower end

with a roller 47. The roller 47 normally rests on the uppermost sheet of the bulk of paper 36 which is carried on the platform 33 and it will be readily observed that when the paper is fed to the printing or folding machine, the roller and the arm will gradually move downwardly. On its projecting end, the shaft 33 also carries a depending arm 48 which is fixedly carried thereby and which is pivotally connected to a connecting arm 49. The opposite end of the connecting arm 49 is pivotally connected to the disc wheel 37 as at 50 at a point adjacent its periphery as shown in Figures 1 and 4. From this construction, it will be observed that as the paper is fed from the bulk 36 and the arm and roller 46 and 47 move downwardly, the disc wheel 37 will be moved by the arm 48 and the connecting arm 49 so as to position the cam 38 away from the pawl 40. However, as the platform 33 moves upwardly and the arm 46 and the roller 47 are moved in a similar direction, the cam 38 will be brought near the pawl 40 until finally it engages the pawl and moves it out of engagement with the ratchet wheel 36 so as to cause a discontinuance of the operation of the shaft 18 and the elevation of the platform 33. In other words as the arm 46 and the roller 47 raise and lower, the operation of the shaft 18 will be controlled automatically as will the elevation of the platform 33.

In order to prevent retrograde movement of the ratchet wheel 36 when the pawl 40 is out of engagement therewith, I provide the adjacent bearing portion 15 with a pawl 51 which remains in engagement with the ratchet wheel at all times. However, inasmuch as the pawl 51 is stationary and does not move with the pawl 40, it will be observed that the only function performed thereby is to prevent reverse movement of the ratchet wheel 36.

On the opposite end of the shaft 18, I may arrange a handle 52 whereby the elevator may be operated, manually, for instance, to return the platform 33 to its normal and lowermost position. The handle may be of any desired form.

From the foregoing it is believed that the advantages and novel features of my invention will be readily understood and therefore further detailed description is deemed unnecessary.

What is claimed is:—

In a device of the character described, a supporting structure, vertically disposed worm shafts carried by said supporting structure, a platform having openings to receive said worm shafts, bevelled gears carried at the upper end of said worm shaft, a shaft mounted transversely across said body portion and superimposed above said platform, bevelled gears carried on said

shaft meshing with said first named bevelled gears, a ratchet wheel fixed to said second named shaft, an arm loosely mounted on said second named shaft, a pawl carried by 5 said arm normally engaging said ratchet wheel, means whereby said arm may be rocked whereby said second named shaft will be rotated so as to cause rotation of said worm shaft and the consequent operation of said platform, a disc member loosely 10 mounted on said second named shaft, means on said disc member engageable with said pawl at certain times to move the latter out of engagement with said ratchet wheel, 15 a second shaft superimposed above said platform and arranged transversely across said body portion, means loosely connecting said last named shaft and said disc member whereby upon partial rotation of said last named shaft, the disc member will be moved 20 so as to throw said pawl out of engagement with said ratchet wheel and means carried by said last named shaft engageable with the material carried on said platform, substantially described. 25

In testimony whereof I affix my signature in presence of two witnesses.

FRED E. WEED.
